his Atty.

UNITED STATES PATENT OFFICE.

HERBERT C. FOLLINGER, OF CHICAGO, ILLINOIS, ASSIGNOR TO CHAIN BELT COMPANY, OF MILWAUKEE, WISCONSIN, A CORPORATION OF WISCONSIN.

COOLING-TANK.

1,384,311.

Specification of Letters Patent. Patented July 12, 1921.

Application filed June 10, 1919. Serial No. 303,223.

To all whom it may concern:

Be it known that I, HERBERT C. FOLLINGER, a citizen of the United States, and a resident of Chicago, in the county of Cook 5 and State of Illinois, have invented certain new and useful Improvements in Cooling-Tanks, of which the following is a full, clear, and exact specification.

My invention is concerned with cooling 10 tanks designed for taking hot cans filled with corn or other materials as they come from the cooker and cooling them with a minimum of trouble and expense, and without the possibility of deforming or opening 15 the cans so as possibly to cause a leakage and ultimately spoil the contents of the cans so deformed.

To this end, it consists of an endless conveyer mounted in a trough kept supplied 20 with cool water and operating so that the hot cans can be dumped into the water and onto one end of the continuously moving conveyer and carried thereby through the length of the trough and up out of the 25 cooling water to the point of discharge.

To illustrate my invention, I annex here- 30 to two sheets of drawings in which the same reference characters are employed to designate identical parts in all the figures of which—

Figure 1 is a top plan view of a portion of the cook room of a canning factory having my invention installed therein, a portion of the central part of the apparatus 35 being broken away to shorten the length of the view;

Fig. 2 is a side elevation of the same in section on the line 2—2 of Fig. 1;

Fig. 3 is a detail in section on a larger 40 scale on the line 3—3 of Fig. 1;

Fig. 4 is a similar view but on a still larger scale and looking in the opposite direction from Fig. 3;

Fig. 5 is a side elevation of a portion of 45 the mechanism seen in Fig. 4, but taken at another point where the ends of two sections of the wooden side pieces meet;

Fig. 6 is a detail in vertical section on the line 6—6 of Fig. 2; and

Fig. 7 is a side elevation of the mechanism 50 seen in Fig. 6 as seen from the right-hand side of said figure.

In the drawings, 10 represents the floor of a portion of the cook room of a canning

factory of which two of the walls 11 and 12 55 are seen in section, and in the preferred form of my invention, the tank 13, which is the basis of my cooling apparatus is formed of concrete and has its top flush with the top of the floor 10, and its bottom 60 about 5 feet below the floor level. At one end, the width of the tank is increased forming a portion 14 substantially square in horizontal cross-section and in this portion 14 on the bottom I mount the framework 15 65 in which is journaled the shaft and sprockets 16 over which the endless conveyer 17 travels. This endless conveyer is made up of a plurality of cypress flights 18 of the proper length to span the width of the 70 trough and having the links 19 of the pair of sprocket chains 20 connected to the under sides thereof. On the upper run, the chain is supported by the angle irons 22, 75 having horizontal flanges projecting inwardly from the sides of the trough and supported in a manner to be subsequently described. On the return run, the ends of the flights preferably travel over the angle irons 23 similarly located and supported so 80 as to avoid undue friction on the bottom of the tank or trough.

Secured to the sides of the trough as by the bolts 24 set into the concrete at suitable intervals are the vertical metallic bars 25, 85 to which are riveted the angle irons 22 and 23, so as to form tracks throughout the length of the tank, which may be say 100 feet long, and at the receiving end, the angle irons 23 are near the bottom, gradually inclining upward until at the point where Fig. 6 is taken in cross-section, the angle irons 22 and 23 are curved to make the final portion of the path of the conveyer through the trough or tank much 95 steeper to more quickly carry the cans out of the cooling water, a constant supply of which at a constant low temperature is maintained by any suitable circulating system. At the end of the tank, the angle irons 100 22 and 23 are again curved to bring them to a horizontal position and in said position they are supported by being riveted or otherwise secured to the standards 26 suitably secured to the floor. At the end of the horizontal metallic framework thus formed, I provide suitable bearings 27 for the shaft 28 of the driving sprocket wheels 29, which 105

has secured thereon the spur-gear wheel 30 driven by the spur-gear pinion 31 secured on the end of the shaft 32 mounted in suitable bearings and having secured thereon 5 the worm-gear 33 driven by the worm 34 secured on the transverse shaft 35 to which is secured belt wheel 36 by which the power is supplied. By means of the train of reducing gearing thus described, it will be 10 obvious that the belt 17 is caused to move very slowly through the length of the trough so as thoroughly to cool the cans and their contents in the cold water with which the tank is filled and finally to carry them out 15 of the tank and to the position above the floor where the cans can be removed manually or shunted onto another conveyer.

The sides of the tank above the angle iron 22 are lined by the boards 37, suitably secured to the vertical pieces 25, and preferably having their meeting ends cut diagonally, as seen in Fig. 5, wherever a joint is necessary. These boards are protected 25 against wear and splintering by the sheet metal guide plates 38, secured on the face of the boards 37 by any suitable means, such as the screws 39, these guide plates preferably having their upper ends 40 inclined over to contact with the walls of the tank. 30 It will be noted that the edges of the conveyer run directly under the boards 37, so as to insure the cans being wholly supported by the conveyer.

At the point where the inclination of the 35 conveyer is increased to lift the cans out of the water, it is necessary to provide an abutment to hold down the upper surface of the conveyer 17 at its edges, and for this purpose, I preferably employ the flanged 40 rollers 41, which cooperate with the edges of the conveyer 17, the body of the periphery contacting with the top of the edge of the conveyer, while the flanges extend below said top, as seen in Fig. 6. To support properly 45 these flanged rollers 41 without causing them to project substantially into the body of the tank or trough, I provide in the walls thereof the vertical recesses 42 in which are secured the bars 43, which in turn support 50 the bearing studs 44 for the rollers 41. The boards 37 are cut away at the points where the rollers 41 are found, but the guide plates 38 are continued across the gap and extend down over the upper part of the 55 rollers 41.

With the construction described, it will be 60 obvious that if the cans filled with the hot, just cooked, contents are dumped into the tank beyond the enlarged end 14, they will settle down on the constantly moving conveyer and will be carried thereby without any displacement relative to each other or to the conveyer throughout the entire length of the tank, as there is no place where there 65 is any contraction of the passageway, and

they will eventually be delivered out of the tank and cooled ready for further handling.

While I have shown and described my invention as embodied in the form which I at present consider best adapted to carry out its purpose, it will be understood that it is capable of some modifications and that I do not desire to be limited in the interpretation of the following claims except as may be necessitated by the state of the prior art. 70

What I claim as new and desire to secure by Letters Patent of the United States is:

1. In a cooling tank, the combination with a trough having the sides slightly overhanging the edges of the bottom, of an endless conveyer therein with its edges on its upper run traveling underneath and adjacent said overhanging sides longitudinal supports for the edges of said conveyer on 85 its upper run, rotating members supporting the conveyer at the ends of the trough, one of said members being above the plane of the top of the trough, means for driving the conveyer, and an abutment on each side of 90 the trough extending over the edges of the belt on its upper run but not beyond the vertical plane of the overhanging sides, and located at the point where the top run of the conveyer turns upward to carry the cans 95 out of the water.

2. In a cooling tank, the combination with a trough having the sides slightly overhanging the edges of the bottom, of an endless conveyer therein with its edges on its upper run traveling underneath and adjacent said overhanging sides longitudinal supports for the edges of said conveyer on 100 its upper run, rotating members supporting the conveyer at the ends of the trough, one of said members being above the plane of the top of the trough, means for driving the conveyer and a guide roller on each side of 105 the trough journaled therein so that its periphery extends over the edge of the conveyer on its upper run but not beyond the vertical plane of the overhanging sides and located at the point where the top run of the conveyer turns upward to carry the cans 110 out of the water.

3. In a cooling tank, the combination with a trough having the sides provided with wooden strips secured thereto and having a metallic sheathing over and secured to said strips and slightly overhanging the 115 edges of the bottom, of an endless conveyer therein with its edges on its upper run traveling underneath and adjacent said overhanging sides, longitudinal supports for the edges of the conveyer on its upper run, rotating members supporting the belt at the ends of the trough, one of said members being above the plane of the top of the trough, means for driving the conveyer, and an abutment on each side of the trough directly over 120

the edges of the conveyer on its upper run but not beyond the vertical plane of the metallic sheathing and located at the point where the top run of the conveyer turns upward to carry the cans out of the water.

4. The combination with a tank, of vertically disposed supporting bars secured to the sides of the tank, rails supported by the said bars for the upper and lower runs respectively of an endless conveyer, lining strips for the tanks secured against the said vertical bars and arranged to be substantially parallel with and to somewhat over-

hang the rails for the upper runs of the conveyer, and an endless conveyer having a 15 flat carrying surface without marginal edges adapted to be supported, near its edges, by the said rails, and the supporting surface thereof extending under the overhanging lining strips.

In witness whereof, I have hereunto set my hand and affixed my seal, this 20th day of May, A. D. 1919.

HERBERT C. FOLLINGER. [s.s.]

Witness:

JOHN HOWARD McELROY.
